Primary Examiner — Cynthia M. Chin(74) *Attorney, Agent, or Firm* — Fross, Zelnick, Lehrman & Sissu PC; Charles T. J. Weigell, Esq.(57) **CLAIM**

The ornamental design for a toy building element, as shown and described.

DESCRIPTION

FIG. 1 is a side perspective view of the toy building element; FIG. 2 is a top perspective view thereof;

FIG. 3 is a left side view thereof;

FIG. 4 is a rear view thereof;

FIG. 5 is a front view thereof;

FIG. 6 is a back elevational thereof;

FIG. 7 is a top elevational view thereof; and,

FIG. 8 is a right side view thereof.

The dash-dot broken lines in FIG. 7 represent the bounds of the claim. All other broken lines represent portions of the toy building element that form no part of the claimed design. None of the broken lines form a part of the claim.

1 Claim, 8 Drawing Sheets# US D981,504 S
